COIN CONTROL MEANS FOR BEVERAGE VENDING MACHINES

Ralph D. Walters, Cleveland, Ohio, assignor of
one-third to William Isler, Cleveland, Ohio

Application June 24, 1946, Serial No. 679,022

4 Claims. (Cl. 194—10)

1

This invention relates, as indicated, to coin control means for beverage vending machines, but has reference more particularly to beverage vending machines of the type in which cups are dispensed singly from the bottom of a stack of cups as the stack descends.

In machines of this type, the operation is such that after the cup has been dropped from the bottom of the stack, the cup is filled with the beverage and is readily accessible to the person who has inserted a coin into the machine.

Heretofore, when the last cup has been dispensed, no means have been provided for discontinuing the operation of the machine, with the result that if the supply of beverage in the machine is greater than that required to fill all of the cups, the excess beverage spills into the opening from which the last cup has been removed, and splatters over anyone who happens to be near such opening. Moreover, no means have been provided in machines of this type for either indicating that the supply of cups is exhausted or has fallen below a predetermined safe minimum, or for returning the coin to the person operating the machine in such cases.

It is a primary object of the invention, therefore, to provide means in beverage vending machines of this type, for causing the machine to become inoperative when the supply of cups has fallen below a predetermined safe minimum, or, stated in another manner, when the stack of cups has fallen below a predetermined level.

Another object of the invention is to provide means, in a beverage vending machine of this type, for giving the user of the machine or others interested in the operation of the machine, a visual or other indication that the machine has been rendered inoperative due to the above-mentioned causes.

A further object of the invention is to provide, in a beverage vending machine of this type, means for causing a coin which has been inadvertently inserted into the machine, after the machine has thus been rendered inoperative, to be returned to the person thus inserting the coin.

Other objects and advantages of the invention will be apparent during the course of the following description.

In the accompanying drawings, forming a part of this specification, and in which like numerals are employed to designate like parts throughout the same,

Fig. 1 is a plan view, showing in a more or less diagrammatic manner, an assemblage of elements or parts used in a typical beverage vending ma-

2

chine, including a cup-dispensing unit, coin-controlled means for operating the cup-dispensing unit, and the novel means to which reference has been made above;

Fig. 2 is a front elevational view of the elements or parts shown in Fig. 1;

Fig. 3 is a fragmentary cross-sectional view, taken on the line 3—3 of Fig. 1, and

Fig. 4 is a wiring diagram for the elements or parts shown in Figs. 1, 2 and 3.

Referring more particularly to the drawings, reference numeral 1 designates a generally cylindrical cup dispenser in which a stack of nested paper cups C is mounted, mechanism being provided for lowering the stack in steps equivalent to the distance between the rims of the cups as shown in Fig. 2, and, at the same time, dropping or releasing the lowermost cup from the stack, so that such cup falls on a platform, not shown, where such cup is filled with a beverage by means well understood in the art, but not necessary to be described.

The cup dispensing mechanism, in this instance, comprises a series of oscillatable elements 2, which are spaced circumferentially about the dispenser 1, in an enlarged annular portion 3 thereof, and which, in one position of their oscillatory movement, support the rim of the lowermost cup (thereby supporting the entire stack of cups), and in another position of their oscillatory movement, release the lowermost cup from the stack.

For the purpose of oscillating the elements 2, each element is mounted for movement about a vertical axis or shaft 4, and has secured thereto a pinion 5, all of the pinions being in mesh with a ring gear 6. The ring gear, at one point in its periphery, is provided with an ear or lever 7, which extends through a slot or opening 8 in the

wall of the annular enlargement 3 of the dispenser 1. The outer end of the lever 7 has pivotally connected thereto one end of a link 9, the other end of which is pivotally connected to a lever 10 which is secured, as by a set screw 11, to the shaft 4 of a motor 13. During each complete rotation of the motor 13, the ring gear 6 oscillates between the extreme positions indicated by the solid and dot-dash lines in Fig. 1, to thereby release the lowermost cup from the stack of cups and permit the stack to descend a distance equivalent to the distance between the rims of the cups.

The aforesaid cup dispensing mechanism is not a part of applicant's invention, but has been described in sufficient detail to render understandable the cup dispensing action and function. For

further details of this cup-dispensing mechanism, reference may be had to United States Patent No. 2,268,421, although it is to be understood that the invention is not limited to the use of such a cup-dispensing mechanism, and that any other type of cup-dispensing mechanism which is available can be used.

The motor 13 is driven from a source of power, indicated by the power lines 14 and 15, the current reaching the motor from the power line 14 through a lead 16. The current from the power line 15 reaches the motor 13 through a path defined by the line 17, switch arm 18, contact 19, contact 20, switch arm 21, line 22, switch arm 23, contact 24, contact 25, switch arm 26, line 27 and lines 28 and 29. It may be noted, at this point, that the switch 23-26 is normally open, but is adapted to be closed by the vertical movement of a coin which bears against the trigger 30 of the switch arm 26 with sufficient weight to bring the contacts 24 and 25 together, the coin thereafter descending into a suitable receptacle, as is common in beverage vending machines of this type.

Rigidly secured to the shaft of the motor 13 is a disc 31 having a peripheral recess 32, which is adapted for the reception of the detent 33 of an arm 34 which is movable about a pivotal axis 35, the arm 34 being attached to the switch arm 18 as at 36. The detent 33 normally bears against the peripheral edge of the disc 31 and at such time, the arm 34 is biased toward the switch arm 21 in such a manner that the contacts 19 and 20 are closed, that is to say, the switch 18-21 is normally closed. As the motor 13 completes a single revolution in the direction indicated by the arrow in Fig. 4, the disc similarly completes a revolution and at the end of such revolution, the detent 33 automatically enters the recess 32 in the disc, thereby opening the switch 18-21 and stopping the motor. The momentum of the disc 31, however, is sufficient to carry the recess 32 beyond the detent 33, the detent stopping at a point indicated at S in Fig. 4, thereby again closing the switch 18-21. No current will pass to the motor, however, since the switch 23-26 has, in the meantime, opened.

When the switch 23-26 is closed, and the circuit to the motor 13 thus energized, it is necessary to maintain the circuit closed after the coin has passed the trigger 30. This is accomplished by the closing of a relay circuit consisting of the line 28, a line 37, switch arm 38, contact 39, contact 40, pivotally mounted switch arm 41, line 42, line 22, switch arm 21, contacts 20 and 19, switch arm 18, and lines 17 and 15, the other side of the circuit consisting of power supply line 14, and line 16. The switch 38-41 is normally open, but is closed when the switch 23-26 is closed by the coin, due to the action of a relay coil 43, which acts on the arm 41 to close the contacts 39 and 40, when the coil 43 is energized. The coil 43 is energized by a circuit consisting of power line 14, line 16, a line 44, line 45, line 37, switch arm 38, contacts 39 and 40, switch arm 41, line 42, line 22, switch arm 18, contacts 19 and 20, switch arm 21, lines 22 and 17, and power line 15. When the switch 18-21 is opened at the end of the revolution of the motor, the relay circuit opens.

An important feature of the invention comprises means for (a) preventing operation of the machine, i. e., operation of the motor 13, when the supply of cups has reached a predetermined minimum, (b) causing a return of the coin at

such time, and (c) causing a signal, in the form of an incandescent bulb readily visible from the front of the machine, to be lighted to indicate that the machine is not operable and that the supply of cups needs replenishment.

For the above purposes, the following circuits and equipment is provided.

A line 46 extends from power line 15 to a contact arm 47 carrying contacts 48 and 49 at opposite sides thereof. The arm 47 is provided at its upper end with a bar 50 which bears against an armature 51 which carries an arm 52, the armature 51 being pivotally movable about a point 53. The portion of the armature beyond the pivotal point 53 is connected to a stationary part 54 by means of a weak tension coil spring 55. The armature 51 is movable in one direction by means of the aforesaid spring 55, and in the other direction by a relay coil 56, which is energized by a circuit, one side of which consists of line 58, line 28, line 37, switch arm 38, contacts 39 and 40, switch arm 41, line 42, line 22, switch arm 21, contacts 20 and 19, switch arm 18, line 17 and power line 15.

A coin return relay coil is indicated at 59, this coil being adapted to act upon an armature 60, which carries a by-pass trigger 61. This coil is energized by a circuit, one side of which consists of a line 62, line 63 and power line 14, and the other side of which consists of line 64, contact arm 65, contact 66, contact 48, contact arm 47, and power line 15.

The signal light is indicated at 67, and this light is adapted to be energized by a circuit, one side of which consists of power line 14, line 68, and line 69, and the other side of which consists of line 69, contact arm 70, contact 71, contact 49, contact arm 47, and power line 15.

The arm 52 extends through a slot or opening 72 in the cup dispenser 1, and normally bears against the rims of the cups C, due to the action of the spring 55, as clearly shown in Figs. 1, 3 and 4.

The machine further includes a coin receiving box, which is more or less diagrammatically illustrated, such box having a coin-receiving opening 73 and a coin chute 74 (Fig. 2), from which the coin passes into a coin receptacle (not shown). As shown in Figs. 1 and 2, the coin-return relay, consisting of elements 59, 60 and 61, is mounted on the back of the coin box.

The relay coil 56, and elements associated therewith, including elements 47, 48, 49, 50, 51, 52, 53, 54, 55, 56, 65, 66, 70 and 71, are mounted directly on the cup dispenser 1, as clearly shown in Figs. 1, 2 and 3.

The operation of the coin control means will now be described, it being noted at the outset that the contacts 66 and 48 are in engagement with each other, that the arm 52 bears against the cup rims, and that the coin-return trigger 61 is in a retracted position, as shown in Fig. 1, this latter position being maintained by the action of the relay coil 59 on the arm 60.

Upon deposit of a coin of the required denomination into the opening 73 in the coin box, the coin will descend through the chute 74 and pass into a suitable coin receptacle (not shown). As the coin emerges from the chute 73, it strikes the trigger 30, biasing the switch arm 26 toward the switch arm 23, thereby closing this switch and energizing the motor circuit in a manner which has been previously described and causing the lowermost cup in the stack to be dropped from the cup-dispensing mechanism.

During the single revolution of the motor 13, which constitutes a vending cycle, the relay coil 56 is energized, causing the arm 52 to be retracted slightly from engagement with the cup rims, and thereby relieving the pressure of this arm against such rims, which pressure, unless it is virtually reduced to a zero pressure, would interfere with the downward movement of the stack of cups, and interfere with the cup-dispensing operation.

At the termination of the aforesaid vending cycle, the relay coil 56 is de-energized, permitting the spring 55 to return the arm 52 to its original position in contact with the cup rims. This return movement of the arm 52 to its original positions is not of sufficient magnitude to break the engagement between contacts 66 and 48. By thus maintaining the engagement between contacts 66 and 48, the coil 59 remains energized, and the trigger 61 remains in retracted position, permitting further operation of the machine.

When the uppermost level of the stack of cups, i. e., the rim of the uppermost cup in the stack, drops below the lower edge of the arm 52, this arm, due to the action of the spring 55, moves to the right from the position shown in Figs. 3 and 4, thereby causing the engagement between contacts 66 and 48 to be broken, and contact made between contacts 49 and 71. This causes the circuit to the signal light 67 to be energized, and the circuit to the coil 59 to be de-energized. When the circuit to the coil 59 is de-energized, a spring 88 (Fig. 1), causes the arm 68 to pivot in such a manner as to cause the trigger 61 to enter an opening 81 in the rear plate of the coin box and to project into the chute 74, as shown in Fig. 2. Thereafter, upon any attempt to insert a coin into the machine, the coin will strike the trigger 61 and by-pass the chute 74, passing out of the coin box to another chute from which it may be retrieved by the person attempting to operate the machine. In this manner, the signal light, as well as the inability to operate the machine will serve as a double indication that the supply of cups requires replenishment.

It will be understood that the invention is not limited to the use of the specific cup dispenser shown, or to the specific mechanism for operating the cup dispenser, these being illustrated and described for the purpose of clearly understanding the complete operation of the machine.

It is to be understood that the form of my invention, herewith shown and described, is to be taken as a preferred example of the same, and that various changes in the shape, size and arrangement of parts may be resorted to without departing from the spirit of my invention, or the scope of the subjoined claims.

Having thus described my invention, I claim:

1. In a beverage dispensing machine, the combination of an electrical circuit, coin-actuated means for closing said circuit, means responsive to closing of said circuit for dispensing cups from a stack of cups disposed in said machine, a movable armature element yieldably engaging said stack and restrained from forward movement by said stack, and an electromagnet operatively associated with said armature element and effective to retract said element in response to energization of said circuit whereby said element is withdrawn from engagement with said stack during the dispensing of said cups.

2. In a beverage dispensing machine, the com-

bination of an electrical circuit, coin-actuated means for closing said circuit, means responsive to closing of said circuit for dispensing cups from a stack of cups disposed in said machine, a movable armature element yieldably engaging said stack and restrained from forward movement by said stack, an electromagnet operatively associated with said armature element and effective to withdraw said element from engagement with said stack in response to energization of said circuit, a second electrical circuit, an electromagnet disposed in said second-named circuit, means movable in response to deenergization of said second-named electromagnet for diverting coins from said coin-actuated means, and switch means connected to said armature element for deenergizing said second-named electromagnet in response to unrestrained forward movement of said armature element.

3. In a beverage dispensing machine, the combination of an electrical circuit, a coin-receiving member, coin-actuated means for closing said circuit, means responsive to closing of said circuit for dispensing cups from a stack of cups disposed in said machine, a movable armature element yieldably engaging said stack and restrained from forward movement by said stack, an electromagnet operatively associated with said armature element and effective to withdraw said element from engagement with said stack in response to energization of said circuit, and means operatively associated with said coin-receiving member for disabling said coin-receiving member in response to unrestrained forward movement of said armature element.

4. In a beverage dispensing machine, the combination of an electrical circuit, a coin-receiving member, coin-actuated means for closing said circuit, means responsive to closing of said circuit for dispensing cups from a stack of cups disposed in said machine, a movable armature element yieldably engaging said stack and restrained from forward movement by said stack, an electromagnet operatively associated with said armature element and effective to withdraw said element from engagement with said stack in response to energization of said circuit, a second electrical circuit, electrically energizable signal means disposed in said second-named circuit, a third electrical circuit, switch means connected to said armature elements and normally closing said third-named circuit, said switch means being movable in response to unrestrained forward movement of said armature element to break said third-named circuit and close said second-named circuit whereby to energize said signal means, and means engageable with said coin-receiving member for disabling said coin-receiving member in response to deenergization of said third-named circuit.

RALPH D. WALTERS.
